UNITED STATES PATENT OFFICE

158,181

ACCORDION

Aurelio Cupido, New York, N. Y.

Application March 11, 1948, Serial No. 145,019

Term of patent 3½ years

(Cl. D56—1)

To all whom it may concern:

Be it known that I, Aurelio Cupido, a citizen of the United States, residing in New York, State of New York, have invented a new, original, and ornamental Design for an Accordion, of which the following is a specification, reference being had to the accompanying drawing, forming part thereof.

Fig. 1 is a front perspective view of the accordion, showing my new design;

Fig. 2 is a top plan view thereof;

Fig. 3 is a side elevational view thereof.

I claim:

The ornamental design for an accordion, as shown.

AURELIO CUPIDO.
